UNITED STATES PATENT OFFICE.

JACOB H. SCHEUER, OF NEW YORK, N. Y.

DESIGN FOR A HAIR-BRUSH.

48,399.

Specification for Design.

Patented Jan. 4, 1916.

Application filed December 8, 1914. Serial No. 876,156. Term of patent 3½ years.

To all whom it may concern:

Be it known that I, JACOB H. SCHEUER, a citizen of the United States, residing in the city, county, and State of New York, have invented a new, original, and ornamental Design for Hair-Brushes, of which the following is a specification, reference being had to the accompanying drawing, forming part hereof.

In the drawing, Figure 1 is a top plan view of a hair brush showing my design; and Fig. 2 is a side elevation thereof.

I claim—

The ornamental design for a hair brush as shown.

JACOB H. SCHEUER.

In the presence of—

HENRY LICHTENSTEIN,
MAURICE KUHE.
